UNITED STATES PATENT OFFICE

2,573,259

INSULATED CONTAINER FOR BOTTLES

Melvin Goldwater, New York, N. Y.

Application August 28, 1948, Serial No. 46,689

1 Claim. (Cl. 229—14)

1

This invention relates to containers and in particular to one used for holding a nursing bottle.

A particular object of the invention is to provide a container of the character referred to which controls the heat or cold loss from a bottle so that certain timed feeding of infants can be accomplished without the necessity of heating the milk or chilling other fluids at such feeding times.

Another object of the invention is to provide a container having a minimum number of dead air spaces so that the body of air surrounding the bottle will have a uniform insulating effect which will closely control the change of temperature so that a bottle of hot milk, for instance, placed in the container at a certain time will be at the proper temperature for feeding an infant at a specified time.

Further objects of the invention are to provide means for mounting an inner tubular container in such suspended relation with an outer jacket that a single air space surrounds the sides and bottom of the container; to provide mounting means for the container so that in manufacture, the inner container and the outer jacket may each be made separately and completely to facilitate assembly; use fewer parts than heretofore found necessary in the making of similar devices; to keep the cost of the product at a minimum and produce a strong, durable, sanitary container that can be used repeatedly.

With these and other objects in view, the invention comprises certain constructions herein-after described and then particularly pointed out in the claim and a preferred embodiment of my invention is illustrated in the accompanying drawing, in which:

Figure 1 is a view in perspective showing the outward appearance of the bottle receptacle,

Figure 2 is a vertical section through the container taken on the line 2—2 of Figure 1,

Figure 3 is a fragmentary vertical section taken at the periphery of the container and greatly enlarged to show the details of construction, and

Figure 4 is a view in section of a piece of a spacer disk used in suspending the inner tube or receptacle.

Referring to the drawing in detail, 10 indicates a bottle holder made from inner and outer tubular sections 11 and 12 respectively which will be hereinafter referred to as the container and the jacket. Both sections are made from a suitable insulating material such as cardboard,

asbestos or fiber board and are tubularly shaped so that the container 11 is positioned concentrically in the jacket 12 will be spaced from the latter at its side and bottom to provide a single dead air space that will serve as an insulating medium.

The lower end of the jacket 12 is closed by a bottom disk 13 of metal or plastic whose edge is beaded as at 14 to enfold the lower edge of the material to securely hold the bottom in place, and prevent air leakage. The lower end of the container 11 is likewise closed by a bottom disk 15 whose beaded edge 15A seals the bottom of the container to prevent the passage of air and also securely grips the material to provide a support for a bottle placed therein, as indicated in outline in Figure 2.

The upper end of the jacket 12 is provided with a circinate spacing disk 16 beaded as at 17 about its periphery for gripping attachment to the upper edge of the jacket material and shaped to provide an annular inwardly and downwardly directed flange 18. The inner diameter of the disk flange 18 is less than the outer diameter of the container 11 and the lower edge of the tapered flange is slightly crimped as at 20, to permit the flange to yield and grip the outside of the container so that, as the latter is forced downwardly through the disk, the bottom edge of the latter embeds itself in the material as shown in Figure 3.

The upper end of the container is covered by a guide band 21 beaded as at 22 over the upper edge of the container material and constituting a stop means. When the container is forced down through the ring, the material of the container may yield, but when the lower edge of the band 21 passes the flange 18 the material no longer yields and the crimped edge 20 of the flange digs into the material to provide a locking means which prevents withdrawal or rising movement of the container out of the jacket. The band 21 and the flange 18 coact to firmly fix and hold the container axially of the jacket and the bead 22 supports the container in suspended relation to the disk 16 to provide a single insulating air chamber about the sides and bottom of the container so that a uniform insulating effect is obtained by the free circulation of air in the chamber. The spacer disk 16 acts as a closure for the upper part of the chamber and prevents leakage of air.

The holder is closed by a cover 24 whose tubular section 25, made of the same material as the container and jacket, extends down over the outer side of the jacket with a snug sliding fit. The

cover is closed completely at one end by a crown disk 26 beaded as at 27 to grip and hold together the upper flared edge of a cup-shaped metal shell or cap 28 and the upper edge of the material. The side wall 29 of the cap abuts the inner surface of the portion 25 and serves as a reinforce for the upper end of the holder. The bottom 30 of the cap may be flat as in Figure 2 or may be shaped to provide a well 31 at the center thereof as shown in Figure 3. This well increases the depth of the insulating chamber; serves as a guide in putting the cover on and also prevents excessive endwise movement of the bottle in the container.

The inner walls of the container and jacket may be covered with foil or any material offering a slick surface that can be easily kept clean and sanitary and will allow the bottle to be easily slid into the container and withdrawn therefrom particularly when moist or damp.

My invention is not to be restricted to the precise details of construction shown since various changes and modifications may be made therein without departing from the scope of the invention or sacrificing the advantages derived from its use.

What I claim is:

A receptacle of the character described comprising concentrically spaced inner and outer tubular sections constituting an inner container and an outer jacket, respectively, bottom disks closing each section, a circinate spacing disk disposed in the upper end of the jacket and having a central opening, said disk having a peripheral

5 bead for gripping engagement over the upper edge of said jacket and a depending crimped flange bounding said opening, a relatively wide guide band fitting into the upper open end of the container and having a bead for gripping engagement with the upper edge of said container, said band coacting with said crimped flange for gripping the container and holding the same in place concentrically of and spaced from said 10 jacket and in spaced relation with the bottom disk of said jacket, a tubular section slidably fitting over the upper end of the jacket, a cup-shaped cap closing one end of the tubular section to complete a cover for the jacket, and said cap being 15 shaped to provide an inwardly extending well concentrically thereof and constituting a guide projecting into said band to provide a closure for the container, a crown disk fitted into the upper edge of said cap to provide with the cap a 20 sealed air chamber and the cap being arranged to seat on said peripheral bead when the cover is in place.
